UNITED STATES PATENT OFFICE.

ALBERT GLENISTER, OF HIGH WYCOMBE, ENGLAND.

CHAIR, COUCH, OR THE LIKE.

1,301,836.

Specification of Letters Patent. Patented Apr. 29, 1919.

Original application filed August 26, 1916, Serial No. 116,977. Divided and this application filed December 5, 1917. Serial No. 205,570.

To all whom it may concern:

Be it known that I, ALBERT GLENISTER, a subject of the King of Great Britain and Ireland, residing at High Wycombe, in the county of Buckingham, England, have invented certain new and useful Improvements in Chairs, Couches, or the like, of which the following is a specification.

This invention relates to chairs, couches or the like and more particularly to those which are provided with an angularly adjustable back-member which may be under spring action tending to return same to raised or normal position. A chair of the character specified is shown and described in my prior application, Serial No. 116,977, filed August 25, 1916, of which the present application is a division.

The invention consists in certain novel features of construction, hereinafter fully described and specifically claimed, these features including a locking device for the back-member of the type which includes a notched plate engageable by a bolt under control of the occupant, the improved construction comprising a lever pivotally mounted outside a frame member in a vertical direction with a spring bolt connected to said lever, and the notched plate secured to the side of the back-member between the latter and the frame and adapted to be engaged by the spring bolt.

A latch is provided adapted to engage the lever for rendering the spring bolt inoperative at will.

The back member is pivoted in the frame by means of a cross-rod, which is located at the base of the back-member and inclosed by said member for substantially its entire length, the protruding ends of said rod being pivoted in fixed relationship to the frame in bearing plates detachably connected to the inside of said frame, and held in said bearing plates by cotter pins.

Referring to the accompanying drawings:

Figure 1 is a sectional elevation showing a chair having the present improvements applied thereto;

Fig. 2 is a detail side elevation on an enlarged scale showing part of the back-member and the locking device for holding same in adjusted position.

Fig. 3 is a vertical section of Fig. 2 on the line A—B.

In said drawings the chair is shown as comprising front and rear legs or uprights a^1 and a^2 respectively, arms a^3 , a back-member b and seat member c , the latter being pivoted at its front end at c^3 to a cross frame member a^4 , this seat member being under the action of a spring c^7 and coupled to the back member b as by eye bolt connections c^4 . The back-member is shown as suitably upholstered, and it may be formed in any appropriate manner, this member being pivoted in the rear uprights a^2 by means of a rod b^1 extending through the back-member so as to be hidden from view. The protruding ends of said rod each rest in a slot in the upper end of a bearing-plate b^2 secured to the inside face of each of the uprights a^2 as by screws b^3 , and the rod is secured against accidental removal from said slots by means of cotter pins b^4 . The said protruding ends of the rod between the back-member and the bearing-plates are encircled by thick washers b^5 secured to the back-member as by screws b^6 and which serve to prevent the rod from working loose on the back-member and maintain it in position between the bearing-plates.

The locking-device for securing the back-member in desired position comprises a plate d secured outside one of the rear-uprights a^2 and a second plate d^1 secured to the inside thereof, each as by screws d^3 . These plates form bearings and guides for a spindle d^5 having at its end a catch d^4 under the action of a spring d^6 and pivoted outside the chair to one end of a lever d^7 fulcrumed at d^8 in lugs d^9 formed on the plate d , the opposite end of said lever being enlarged as at d^{10} for ready manipulation by the hand of the occupant. The spring d^6 tends to force the catch d^4 into engagement with one of a number of notches e^1 formed in a curved plate e secured to the side of the back-member, so that said back-member may be held in any position of adjustment corresponding to said notches and may be released by the occupant of the chair by pressing upon the end d^{10} of the lever d^7 ; but for the purpose of allowing the back-member to have freedom of movement I provide a latch f pivoted to the plate d and adapted to engage and retain the lever in the depressed position mentioned whereby the catch d^4 cannot engage the notches in the curved plate e .

What I claim as my invention and desire

to secure by Letters Patent of the United States is:—

1. A chair or couch, comprising, in combination, a frame comprising front and rear uprights, one of the rear uprights being formed with a horizontal aperture which opens through its opposite side faces; a back member pivotally mounted between said rear uprights and having a notched plate secured to its outer side face directly opposite the inner end of said aperture; a bearing plate secured to the outer side face of the apertured upright and provided with an opening registering with the outer end of the said aperture; a lever fulcrumed intermediate its ends on the bearing plate; a bolt slidably mounted in said aperture and projecting at its inner end through the inner end of the aperture for engagement with the notched plate, the outer end of said bolt projecting through the opening in said bearing plate and being pivotally connected to the adjacent end of said lever; a spring in said aperture encircling said bolt and tending to force it inwardly therethrough to engage said notched plate, thereby holding the free end of said lever away from said bearing plate.
2. A chair or couch, comprising, in combination, a frame comprising front and rear uprights, one of the rear uprights being formed with a horizontal aperture which opens through its opposite side faces; a back

member pivotally mounted between said rear uprights and having a notched plate secured to its outer side face directly opposite the inner end of said aperture; a bearing plate secured to the outer side face of the apertured upright and provided with an opening registering with the outer end of the said aperture; a lever fulcrumed intermediate its ends on the bearing plate; a bolt slidably mounted in said aperture and projecting at its inner end through the inner end of the aperture for engagement with the notched plate, the outer end of said bolt projecting through the opening in said bearing plate and being pivotally connected to the adjacent end of said lever; a spring in said aperture encircling said bolt and tending to force it inwardly therethrough to engage said notched plate, thereby holding the free end of said lever away from said bearing plate; and a latch pivoted to said bearing plate adjacent the said free end of the lever in position to engage said end when pressed inward toward the bearing plate against the action of said spring, so as to retain said bolt in disengaged relation to said notched plate.

In witness whereof I have signed this specification in the presence of two witnesses.

ALBERT GLENISTER.
